FIRE EXTINGUISHER

Guy L. Tinkham, Detroit, Mich., assignor, by
mesne assignments, to McCord Radiator &
Mfg. Co., Detroit, Mich., a corporation of Maine

Application February 1, 1933, Serial No. 654,606

14 Claims. (CL. 169—31)

This invention relates to pressure operated fire extinguishers of the portable pistol grip type.

In these extinguishers carbon tetrachloride is usually employed as the extinguishing fluid which is retained in a metal barrel-like container forming part of the device. This fluid, when the device is in use, is forcibly discharged therefrom in the form of a stream by pressure released on the puncturing of a pressure supplying cartridge with which the device is equipped. The cartridge usually contains a charge of carbon dioxide gas compressed to liquid form and thus when released on puncturing the cartridge will create an extremely high pressure on the extinguishing liquid in the container to forcibly eject it therefrom a considerable distance upon the opening of the discharge orifice of the extinguisher. This orifice is controlled by a valve and the cartridge is punctured in the initial opening of the valve.

The pressure stored in the cartridge by compressing this gas to liquid form is approximately 900 pounds to the square inch, thus clearly indicating that the contents of the container is under an exceedingly high pressure when the cartridge is punctured.

The cartridge is punctured through the actuation of a firing pin which in the form of extinguishers as heretofore generally made is slidably mounted on the container and extends into the container to reach the cartridge which is in the container. In these extinguishers, the outer end of the pin is connected with and operated by a trigger at the pistol grip of the device. The discharge valve is controlled by the trigger, the stem of the valve being slidably mounted in the portion of the device providing the discharge passage. The valve stem extends out of this passage and has its outer end connected with the trigger. The arrangement is such that the trigger controls both the firing pin and the discharge valve, opening the latter on the release of the pressure from the cartridge so that the extinguisher is put in operation the instant the trigger is pulled toward the pistol grip in the manner of firing a gun. A discharge nozzle is disposed at the front end of the device and is arranged to direct a stream of extinguishing fluid forwardly in the direction and at the point at which the device is aimed.

Due to the high pressure developed in the container when the device is in use and due to the fact that the pin and the valve stem extends out of the container and the discharge passage, respectively, it is necessary to pack the pin and the valve stem to prevent seepage about them.

Packing glands with adjustable nuts have been used for this purpose so that the packings can be compressed sufficiently tight to prevent seepage. At the high pressure employed, the joints must be exceedingly tight, thus subjecting the pin and the valve stem to such undue friction that it is almost impossible for the operator to move the pin and the stem by the trigger when operating the device. Loosening the packings to permit the necessary freedom of movement for the pin and the stem would so open the joints that leakage would occur.

Another objection to these extinguishers as heretofore made is the large number of soldering operations required in their manufacture. First, the end of the container must be soldered in place. Second, the cartridge casing mounted in the container must be soldered to the top of the container. Third, the cartridge casing must be soldered to the bottom of the container. Fourth, the stem of the gravity valve fixture inserted in the container must be soldered to the container, and fifth, the lug at the bottom of the container upon which the trigger fulcrums must be soldered to the container. Soldering is not only an expensive operation generally but is a dangerous one in association with fire extinguishers in which carbon tetrachloride is used as the extinguishing fluid. Any trace of soldering flux or soldering acid is apt to unite with the carbon tetrachloride and form hydro-chloric acid which quickly attacks the metal container to its detriment.

The general purpose and object of my invention is to so improve the extinguisher of the character referred to that packing means are not required for the movable parts controlled by the trigger, thereby enabling such parts to be maintained readily and freely movable at all times and thus subject the trigger to no undue resistance when actuated to operate the device.

In carrying out this object I so mount and arrange the firing pin that it extends through a wall dividing chambers which are connected with the interior of the container, thereby dispensing with the need of packing for the pin.

Another object of my invention is to so design the extinguisher that the number of soldering operations is reduced to one, namely, that required for securing the cap to the end of the container itself.

This particular object may be accomplished by making the grip handle and the discharge controlling and pressure supplying assembly independently of each other and the container and mechanically attaching them to the container in-

dependently of each other, thereby requiring only one soldering operation and that for the cap. As the latter fits over the outer side of the container the interior of the container may be kept free of 5 flux and acid.

Other and further objects of my invention will appear from the following specification taken in connection with the accompanying drawing, in which—

10 Fig. 1 is a longitudinal sectional view of a fire extinguisher of the pistol grip type constructed in accordance with my invention; and

15 Figs. 2 and 3 are sectional views taken on line 2-2 and 3-3 respectively of Fig. 1 to show details of construction, parts being shown in elevation for the purpose of illustration.

20 In the drawing, 1 indicates the container of the extinguisher. The container is preferably barrel-like in form and is of a size to contain the desired amount of extinguishing fluid which as heretofore stated is usually carbon tetrachloride. The container may be drawn to the shape required from the desired metal and thus requires only one closure cap, such as 2 at one end. The 25 opposite end of the container is integral with its body as shown. The cap 2 is soldered in place and this is the only soldering operation in the assemblying of the extinguisher device. The cap fits over the outer end of the container and thus 30 may be soldered thereto without leaving any trace of soldering flux or soldering acid.

35 The grip handle 3 is fastened in a manner to be hereinafter described to the underside of the container 1 and is so positioned intermediate the ends of the container that the extinguisher is balanced when held in the hand of the operator. The upper portion of the casing forming the handle 3 is formed to provide a housing 4 for the discharge controlling and pressure supplying assembly for the container. This assembly includes 40 a body member 5 provided with a chamber 6 accommodating a pressure supply cartridge 7. The latter is slidably supported in the chamber 6 and is provided at one end with a readily puncturable closure 8 adapted to be punctured by a needle or pin 9 carried by a nut 10 which closes the outer end of the chamber. A gasket 11 is clamped by the head of the nut against the adjacent end 45 wall of the body member 5 to prevent leakage 50 from the chamber.

55 Member 5 is provided at its end adjacent the nut with an upwardly projecting boss or lug 12 which extends into the container 1 through an opening in its body wall as shown. Lug 12 is threaded on its outer side to receive a nut 13 for securing the member 5 to the container, there being a gasket 14 interposed between the container wall and the member 5 as shown. Lug 12 is provided with two passages 15, 16, the former connecting the chamber 6 with the interior of the container 1. The passage 16 connects the interior of the container 1 with a longitudinal passage 17 in the member 5, the passage 17 being connected by port 18 with a chamber 19 formed in the member 5 in advance of the chamber 6. Passage 17 may be formed in the member 5 by a drilling operation, the outer end of the passage being closed by plug 20 as shown.

70 A valve guide 21 is screwed into the end of the member 5 at the chamber 19 and provides a support for a discharge valve 22. The latter is slidably mounted in the guide and has an axial passage 23. Said passage terminates short of the inner end of the valve member and is there provided with one or more side ports 24 adapted to

connect the passage 23 with the chamber 19 when the valve member is moved into open position by the trigger mechanism to be presently described. When the valve member 22 is closed, its ports 24 are in the bore of the guide 21 in which the valve member is slidably mounted.

5 The inner end of the valve member 22 may be enlarged to provide a head 25 for contact with a firing pin 26 slidably mounted in the wall portion of the member 5 between chambers 6 and 19 as 10 shown. This pin extends into both chambers and is in axial alignment with the valve member 22 and the cartridge 7, respectively, so that when the pin is forced against the cartridge the latter will be moved against its puncturing needle 9. 15 When the cartridge is punctured the stored-up energy therein is released and enters the container 1 through the passage 15 to force the extinguishing liquid out of the container under pressure through the nozzle 27 at the outer end 20 of the valve member 22. Nozzle 27 is screwed into the valve member 22 and has an axial passage 28 connected with the passage 23 in the valve member. The housing 4 is provided in its front wall opposite the nozzle with a discharge 25 opening 29 through which the nozzle discharges the extinguishing fluid from the container in the operation of the device.

Pin 26 is provided with an abutment 30 at its end in the chamber 19 so that the pin will not 30 drop out of the member 5 when changing a cartridge 7. To accomplish this, the nut 10 is removed from the support 5, opening the chamber 6 and permitting the cartridge to be slid out of the same. On inserting a fresh cartridge, the 35 nut 10 is returned, however, first filling the container 1 with a charge of extinguishing fluid through the open chamber.

In applying the needle 9 to the nut 10 in the manufacture of the device, the needle is pressed 40 into a recess in the nut and held in place by rolling the edge of the recess over a shoulder on the needle as indicated at *a* in Figs. 1 and 3. Grooves *b* are impressed in the inner face of the nut radially about the needle to insure escape- 45 ment of the pressure fluid from the cartridge when released.

The trigger mechanism comprises a trigger 31 secured in front of the grip handle 3 and normally protected against accidental operation by 50 a guard 32 as in devices of this general character. The trigger 31 extends into the housing 4 through a slot 33 in its bottom wall, the upper end of the trigger being bifurcated to straddle the valve guide 21 where it projects beyond the 55 body 5. The upper end of the trigger is mounted on an axis pin 34 arranged above the valve guide and fitted in a lug 35 carried by the body 5 and extending forwardly therefrom as shown in Fig. 1. The lug extends between the two arms *c*, *c* of 60 the trigger and provides a mounting therefor independently of both the housing 4 and the container 1. The trigger in its actuation moves the valve member 22 through the nozzle 27. This is accomplished by having the two arms of the 65 trigger connected with the nozzle by a pair of links 36, 36. These links as shown in Fig. 2 are on opposite sides of valve guide 21 and have their opposite ends pivoted to the trigger arms and nozzle, respectively. For the arms, short rivets 70 37, 37 are employed as the connectors, allowing full movement at this point. For the nozzle, an axis pin 38 is employed as the connector for said pin extending through the body of the nozzle above its axial passage as shown. A conical com- 75

pression spring 39 encircles the valve guide 21 and bears at its opposite ends against the nozzle and guide, respectively. The spring urges the valve member 22 forwardly and when the parts 5 are at rest, keeps the ports 24 and the tapered seat *d* on the valve member closed. Said seat fits against the valve guide 21 about the bore therein as shown. Thus there is no likely chance of leakage about the valve member even under the 10 high pressure developed in the container in the use of the device. Moreover, the guide 21 provides a relatively long bearing for the valve member to hold it central with respect to its seat and in axial alinement with the firing pin 26. With 15 the latter extending into both chambers 6 and 18, any leakage along this pin between the chambers would be immaterial as both chambers connect with the interior of the container. Thus the pin may be freely movable in its support 5 and offers no appreciable resistance to the trigger 20 when firing the device. Obviously no packing is required for this construction.

A seal wire 40 is looped through an aperture 41 in the trigger 31 and has its ends secured together about and on opposite sides of the guard 32 by a seal 42. This arrangement is provided to prevent any possible accidental operation of the extinguisher after it has been loaded with a pressure cartridge and a charge of extinguishing fluid. The seal is made to be readily and easily broken on pulling the trigger to discharge the device. The trigger may be made in two parts properly shaped and spot welded together.

The valve fixture for controlling the flow of 35 extinguishing fluid out of the container 1 comprises a housing 43 connected with the passage 16 in the manner shown in the drawing. Casing 43 is provided on opposite sides with tapped lugs 44, 44 to receive fluid conveying conduits 45, 46. 40 These conduits extend to the opposite ends of the container 1, the conduit 46 being of the flexible metal type as shown and having a weight 47 in its outer or free end to keep such end of the conduit lowermost in all positions in which the 45 extinguisher may be held when in use. Arranged in the casing 43 is a gravity weight 48 fulcrumed adjacent its lower end on a pin 49. A sleeve or equivalent member 50 extends through the weight 48 in alinement with the openings 50 provided by the connecting lugs 44. A pin 51 pivotally connects the sleeve 50 with the weight 48, the opening or passage in the weight for the sleeve being made large enough in diameter to permit free oscillation of the sleeve within limits 55 to properly seat the tapered valve members 52, 53 at the opposite ends of the sleeve and within the respective connecting bosses 44, 44 as shown. These bosses have tapered seats for the valve members. Casing 43 is made with an opening 60 at one side, which opening is normally closed by a cover plate 54 secured in place by a suitable number of screws or bolts with a vellumoid gasket between the cover and the body of the casing to provide an air tight joint.

65 The container 1 is secured to the grip handle 3 by a band 55 fitting about the container opposite the handle and is secured to the housing 4 of the handle by a number of screws or bolts 56, 56 as shown.

70 Pulling the trigger 31 toward the grip handle 3 breaks the seal 42, compressing the spring 39 and opening valve member 22. This movement punctures the cartridge 7 and releases its pressure supply. While pulling the trigger to open 75 the valve and puncture the cartridge, the extin-

guisher is aimed or pointed in the direction of the fire to be put out and upon release of the pressure from the cartridge the extinguishing fluid will be forcibly discharged out of the nozzle 27 in the direction of the fire by the pressure exerted on the fluid in the container 1. As heretofore pointed out, the container 1 is charged with its extinguishing fluid at the time of inserting a cartridge 7 in the chamber 6. Only the specified amount of fluid can be poured into the device owing to the proper location of the inlet passage 15. To fill the unit, it is held with the chamber 6 opening upwardly and the extinguishing fluid is poured into the unit through this chamber. The desired room for expansion 15 for the released pressure from the cartridge is allowed in the container 1 due to the fact that the container can only be filled up to the passage 15, the excess flowing out of the open end of the chamber. 20

When the pressure in the cartridge is released, the extinguishing fluid in the container is under pressure regardless of the position in which the device is held for use. When the device is held in a downward position, the weighted lever 48 falls or tilts forward, closing the valve 52 on its rear side and opening valve 53 on its front side. This allows the pressure in the container to force the extinguishing fluid through the flexible tube 46 and out through the passage 16 and 30 17 and those in the valve chamber and nozzle, respectively. With valve 52 closed at this time, there is no loss of pressure from the device. When holding the extinguisher in an upward position, that is, with the nozzle projected upwardly, the action of the weighted lever 48 is just the reverse. It falls rearwardly, closing valve 53 and opening valve 52, thereby allowing the pressure to force the extinguishing fluid out of the container through the pre-formed tube 45 and passages 16, 17, etc. There is no loss of pressure through flexible tube 46 which now extends into the space unoccupied by the extinguishing fluid. 40

When using the extinguisher the flow may be started and stopped at will. By releasing pressure 45 on the trigger 31, the spring 39 will close the valve member 22 and securely shut off the flow to the nozzle 27.

The device shown and described is simple in 50 construction and operation and capable of being readily and easily manufactured without the use of packing means as heretofore and without excess soldering as required by the extinguisher of this type as heretofore made. The body 5 provides a support and mounting for the main 55 operative parts of the device and also enables the valve member, firing pin and cartridge to be arranged in axial alinement for opening the valve and puncturing the cartridge by force applied on the trigger to move it in one direction. 60

The details of construction and arrangement 65 of parts shown and described may be variously changed and modified without departing from the spirit and scope of my invention, except as pointed out in the appended claims.

I claim as my invention:

1. In a fire extinguisher of the character described, a barrel-like container for the extinguishing fluid, and a discharge controlling and pressure supplying assembly made separate from the container and attached to the container on the exterior thereof, said assembly having a pressure releasing firing pin and a trigger mechanism for operating the same, said pin being slidably mounted in a wall in the assembly between 70 75

and dividing two chambers, both connected with the interior of the container, and respectively serving as the pressure supplying and discharge conveying chambers for the container.

- 5 2. In a fire extinguisher of the character de-
scribed, a barrel-like container for the extin-
guishing fluid, and a discharge controlling and
pressure supplying assembly for the container,
said assembly having a valve for controlling the
10 discharge of extinguishing fluid from the con-
tainer, a pressure containing cartridge for sup-
plying pressure to the container, a puncturing
element for the cartridge, a firing pin for mov-
ing the cartridge against the puncturing element,
15 said valve having a stem slidably mounted in
the assembly opposite the firing pin and adapted
for direct contact therewith and a trigger mech-
anism connected with the valve stem for opening
20 the valve and for moving the stem into con-
tact with the firing pin for actuating the same,
all carried by and incorporated in the assembly,
whereby the latter may be made and assembled
25 independently of the container and be attached
thereto as a unitary fixture.

25 3. In a fire extinguisher of the character de-
scribed, a barrel-like container for the extin-
guishing fluid, a fixture on the outer side of the
container and having a valve controlled discharge
30 opening for the container, a pressure supplying
cartridge and a trigger mechanism for punctur-
ing the cartridge to supply pressure to the con-
tainer and opening the valve for discharging the
35 extinguishing fluid from the container, said fixture
having a lug extendable into the container
whereby the fixture may be attached to the con-
tainer, said fixture having discharge and pressure
40 conveying passages connected with the interior of
the container through said lug, and a valve as-
sembly in the container for controlling the flow
of fluid therefrom into said discharge passage,
45 said valve assembly being connected with and
supported by said lug.

4. In a fire extinguisher of the character de-
scribed, a barrel-like container for the extin-
guishing fluid, a member attached to the container on
the outer side thereof, said member having a pair
50 of axially spaced chambers connected with the
interior of the container, a valve guide secured
to the member at one chamber, a valve having a
discharge passage and slidably mounted in said
55 guide for controlling the discharge of the extin-
guishing fluid from the container through said
chamber, a pressure supplying cartridge slidably
mounted in the other chamber for supplying pres-
sure to the container therethrough, a puncturing
60 element for the cartridge carried by the member
at the last named chamber, a pin slidably mounted
in the portion of the member dividing the cham-
bers, a discharge nozzle at the outer end of the
65 valve member and carried thereby and having a
discharge orifice connected with the discharge
passage in the valve, and a trigger mechanism
carried by the member and connected with the
70 valve at the nozzle for moving the valve into open
position and moving the cartridge against its
puncturing element.

5. The extinguisher structure defined by claim
4 in which the puncturing element for the car-
tridge is carried by a closure for the chamber in
which the cartridge is mounted and which closure
75 is accessible for removal from the exterior of the
extinguisher.

6. The extinguisher structure defined by claim
5 4 wherein the puncturing element is in the form

7. The extinguisher structure defined by claim
4 wherein the trigger is formed to straddle the
valve guide and is connected by links with the
nozzle.

8. The extinguisher structure defined by claim
4 wherein the trigger is connected by links with
the nozzle and is fulcrumed on a lug on the mem-
ber extending forwardly over the valve guide to-
ward the nozzle.

9. The extinguisher structure defined by claim
4 wherein a coiled tension spring surrounds the
valve guide and engages the member and the
nozzle respectively, for normally closing the valve.

10. In a fire extinguisher of the character de-
scribed, a barrel-like container for the extin-
guishing fluid, a grip handle attached to the container
20 and having a portion extending along the con-
tainer in space providing relation thereto, and a
trigger actuated-pressure release assembly in-
cluding a trigger, a discharge nozzle and a con-
trolling valve for the nozzle disposed in the space
25 between the container and the grip handle and
attached to the container independently of the
handle whereby the assembly including the nozzle,
the trigger and the pressure furnishing means
30 may be attached to the container as a single inte-
grated fixture prior to the application of the
handle to the container and whereby the handle
may be removed from the container without dis-
connecting the nozzle, the trigger and the other
35 parts of the assembly from the container.

11. In a fire extinguisher of the character de-
scribed, a barrel-like container for the extin-
guishing fluid, a grip handle attached to the container
and having a portion extending along the con-
tainer in space providing relation thereto, and a
40 trigger actuated-pressure release assembly in-
cluding a trigger, a discharge nozzle and a con-
trolling valve for the nozzle disposed in the space
between the container and the grip handle and
attached to the container independently of the
45 handle whereby the assembly including the nozzle,
the trigger and the pressure furnishing means
may be attached to the container as a single
integrated fixture prior to the application of the
handle to the container and whereby the handle
50 may be removed from the container without dis-
connecting the nozzle, the trigger and the other
parts of the assembly from the container, said
assembly having a single attaching lug for attach-
ing the assembly to the container, and discharge
55 and pressure supplying passages connected with
the interior of the container through said lug, the
discharge passage serving the nozzle and the other
passage serving the pressure furnishing means.

12. In a fire extinguisher of the character de-
scribed, a barrel-like container for the extin-
guishing fluid, a grip handle attached to the container
and having a portion extending along the con-
tainer in space providing relation thereto, and a
60 trigger actuated-pressure release assembly in-
cluding a trigger, a discharge nozzle and a con-
trolling valve for the nozzle disposed in the space
between the container and the grip handle and
attached to the container independently of the
65 handle whereby the assembly including the nozzle,
the trigger and the pressure furnishing means
may be attached to the container as a single
integrated fixture prior to the application of the
handle to the container and whereby the handle
70 may be removed from the container without dis-
connecting the nozzle, the trigger and the other
parts of the assembly from the container, said
assembly having a single attaching lug for attach-
ing the assembly to the container, and discharge
75 and pressure supplying passages connected with
the interior of the container through said lug, the
discharge passage serving the nozzle and the other
passage serving the pressure furnishing means.

5 connecting the nozzle, the trigger and the other parts of the assembly from the container, the space providing portion of the handle being in the form of a housing enclosing the assembly on opposite sides thereof along substantially the full length of the assembly and having an opening at its front end for the discharge of fluid therethrough from the nozzle.

10 13. In a fire extinguisher of the character described, a barrel-like container for the extinguishing fluid, said container having a body portion and end walls closing the opposite ends of the same, one end wall being integral with the body portion of the container and the other end wall being in the form of a cap fitting over the adjacent end of the container and soldered thereto, a grip handle and a trigger actuated-pressure release assembly comprising separate fixtures located on the outer side of the container between the ends thereof with the trigger actuated-pressure release assembly between the container and the grip handle, means for attaching the grip handle to the container independently of the trigger actuated-pressure release assembly, and a single attaching lug carried by the latter assembly for connecting the same to the container independently of the grip handle.

15 14. In a fire extinguisher of the character described, a barrel-like container for the extin-

guishing fluid, a member attached to the container on the outer side thereof, said member having a pair of axially spaced chambers connected with the interior of the container, a valve guide secured to the member at one chamber, and extending from the member in alignment with said chamber, said guide having an axial bore extending therethrough and connected at its inner end with said chamber, a valve having a tapered head in the chamber to close the bore when the valve is in closed position, said valve also having a stem fitting and slidably mounted in said bore, a discharge nozzle connected with and carried by the stem at the outer end thereof, said stem having an axially disposed passage, connected at its outer end with the discharge orifice of the nozzle and connected at its inner end with a side port disposed in the stem, said port opening through the periphery of the stem inwardly of the tapered head whereby the port is located within the bore and closed thereby when the valve is in closed position and is carried into the chamber which the valve controls to connect said chamber with the passage in the stem when the valve is moved into open position, and means carried by the member for opening and closing the valve.

20 25 GUY L. TINKHAM.
